(57) **CLAIM**

The ornamental design for a case for liquid crystal display, as shown and described.

DESCRIPTION

FIG. 1 shows a perspective view of the case for liquid crystal display.

FIG. 2 shows a right side elevational view of the case for liquid crystal display.

FIG. 3 shows a top plan view of the case for liquid crystal display.

FIG. 4 shows a front elevational view of the case for liquid crystal display.

FIG. 5 shows a bottom plan view of the case for liquid crystal display.

FIG. 6 shows a left side elevational view of the case for liquid crystal display; and,

FIG. 7 shows a rear elevational view of the case for liquid crystal display.
